UNITED STATES PATENT OFFICE

2,424,055

HOOK CONVEYER

Claude Rousseau, Montmagny, Quebec, Canada

Application July 20, 1944, Serial No. 545,764

1 Claim. (Cl. 198—177)

1

My invention relates to improvements in conveyors in which the material to be transported is suspended from devices rolling on an overhead track.

The object of my invention is: first, to provide a track or race of tubular construction and a continuous flow of unconnected balls rolling inside the track and pushed along by a driving mechanism, with interposed ball-like units provided with supporting hooks, and second, to provide means for switching the transported material from one track section to another.

I attain these objects by the mechanism illustrated in the accompanying drawings in which:

Figure 1 is a transverse section of the tubular track,

Figure 2 is a perpendicular section of said track,

Figure 3 is a transverse section of a ball-like unit with hook attachment,

Figure 4 is a diagrammatic plan of the driving mechanism,

Figure 5 is a plan of the switch,

Figure 6 shows one of the devices used to prevent balls from falling off the idle part of the conveyor,

Figure 7 shows a device used to make and break the necessary electric contacts,

Figure 8 is a diagrammatic plan of track layout with switches set to serve a certain section of the layout,

Figure 9 is a similar plan with switches set to serve another section of the conveyor,

Figure 10 is a diagram of the electrical connections interlocking corresponding switches.

Similar numerals refer to similar parts throughout the several views.

The track suspended to the ceiling or from brackets affixed to walls or columns is made of a metallic tube 1 having underneath a slot 4 through which pass the hooks 5 supported by the ball-like units 3. Balls 2 are inserted between said ball-like units to provide a convenient distance between the pieces of material suspended from hooks 5 (Figures 1 and 2).

Each hook 5 has a shank which travels in the slot and is provided at its upper end with a disk-like bearing portion which engages and suspends the shank and hook from a shaft 7 around which turn two segments of sphere 6 (Figure 3). The hook having a rectangular section cannot turn in the slot 4 and the two segments of sphere act as wheels in the tubular track.

The driving mechanism is shown diagrammatically in Figure 4. It consists of two opposed horizontal wheels 8 passing through openings in the side of the tubular track and having peripheral circular indentations 9 corresponding in size with the balls 2 and units 3. Said wheels are driven at a convenient speed by a mechanism not shown on the figure and consisting of an electric

2

motor and suitable gearing. Said indentations engage and propel the balls through the tubular track.

The switching mechanism is shown in Figure 5 in a position to connect section A of the conveyor with section B of said conveyor, section C being idle. Tracks 10, 11 and 12 are stationary and tracks 13 and 14 are sections of track attached to a plate 15, said plate 15 sliding or rolling on a fixed frame (not shown) to permit changing the flow of balls from section B to section C or vice versa.

A guard plate 16 supported by a collar 17 fixed on track 10 and having an opening corresponding to the section of track 10 prevents the balls from falling off movable track 14 in the illustrated position and off movable track 13 when the switch is in the other position. Plate 18 is a plain obturator supported by collars 19 and 20 on movable tracks 13 and 14 respectively and preventing balls from falling off track 12 in the illustrated position and of track 11 when the switch is in the other position. A plain guard plate 21 secured on collar 22 on track 11 (as illustrated in Figure 6) prevents balls from dropping out of movable track 13 when the switch is in the other position and a plain plate guard secured on track 12 to collar 24 prevents balls from dropping out of movable section 14 in the position of the switch as illustrated.

When the switching is made, it is necessary to stop the flow of balls to prevent clogging and damage to the conveyor or to the driving mechanism. This is obtained by means of electric switches or relays attached to the fixed frame (not shown) supporting the mechanical switch, said electric switches being operated upon by a fingerlike device mounted on a convenient part of the movable part of the mechanical switch. In Figure 5 such a device 25 is secured on track 14 and operates on electric switch 26 in the position illustrated and on electric switch 27 in the other position. (See also Figure 7.) The current passes through only when the mechanical switch is in one of the two extreme positions and is cut when said mechanical switch is in motion. Another fingerlike device 28 acting on electric switch 29 may be added to control another driving mechanism placed on another section of the track; in this case on section C as the electric switch 29 will be operated only when the flow of balls passes in section C.

In the diagram shown on Figure 8, the flow of balls passes from section A to section B, section C remaining idle. In the position diagrammatically illustrated in Figure 9, the flow of balls passes from section A to section C, section B being idle. The corresponding switches 15 and 30 must be operated at the same time and this may be obtained through a mechanical connec-

tion. But such a connection may be difficult, complicated and cumbersome in a busy plant and I obtain the same result by interlocking the two mechanical switches electrically as shown in Figure 10 by placing the corresponding electric switches in series with the corresponding motor. In the figures, 36 is the main supply of current, the corresponding electric switches are respectively 26 and 31, 27 and 32 in series with the motor 34 prime mover of section A, and 29 and 33 in series with the motor 35 prime mover of section C. In this way if one of the conveyor switches is not in its extreme position or if one of the conveyor switches is operated without the corresponding one, the current is cut off and the conveyor is stopped.

In order to permit the proper working of the switch, it is necessary that each section of track A, B and C and also the movable parts of the track forming the switch have a length such that it will hold as nearly as possible an exact number of balls.

I am aware that prior to my invention conveyors have been made of a tubular structure. I therefore do not claim such a combination broadly; but I claim:

A conveyor including a tubular body of indeterminate length with the inner surface of true circular form, the body being formed with diametrically-opposed slots of materially less

width than the diameter of the interior of the body, a series of balls in the bore of the body and shaped for rolling contact with the bore of the body to prevent other than a movement of the balls longitudinally of the body bore, depending hook supports connected to certain relatively-spaced balls and depending through a slot in the body, the hooks and slot being relatively formed to prevent turning movement of the hooks relative to the body, and mechanical means extending through the diametrically-opposed slots in the body and cooperating with the balls to advance the latter in the bore of the body.

CLAUDE ROUSSEAU.
